INVENTOR

Thomas E. Brown Jr.

UNITED STATES PATENT OFFICE.

THOMAS E. BROWN, JR., OF MORRISTOWN, NEW JERSEY.

BASCULE BRIDGE.

1,406,259.

Specification of Letters Patent. Patented Feb. 14, 1922.

Application filed February 12, 1920. Serial No. 358,075.

To all whom it may concern:

Be it known that I, THOMAS E. BROWN, Jr., a citizen of the United States, and a resident of Morristown, in the county of 5 Morris and State of New Jersey, have invented certain new and useful Improvements in Bascule Bridges, of which the following is a specification.

This invention relates to improvements 10 in bascule bridges of the class in which the balance of the moving span is attained by means of counterweights pivotally attached to the rearwardly extended end of the span.

In the usual constructions of this class 15 the counterweight is pivotally hung from the rearwardly extended end of the moving span, i. e. that part of the moving span which extends rearwardly beyond the point of rotation. Cases frequently arise in 20 which the height of the bridge floor above the water is insufficient to admit of the counterweights being placed below the bridge floor without the use of expensive watertight pits, and in these cases to avoid 25 such pits, it is necessary to place the counterweights above the heel of the span and it is obvious that when so placed they must be at a sufficient height above the floor of the bridge to avoid obstruction of the road- 30 way when the bridge is in its closed position.

When the counterweight is suspended from the end of the span, its center of gravity being below the support, it is in stable 35 equilibrium, but when it is placed with its center of gravity above its supporting pivot, obviously it is then in unstable equilibrium and means must be provided to prevent its falling over.

40 Heretofore the means used to stabilize or prevent the counterweight from falling over has consisted of fixed towers, frames and the like with links, guides or guys to the counterweight and it is a principal object 45 of my invention to stabilize the counterweight without the use of such fixed towers or frames.

Another object of my invention is to so 50 construct and arrange the stabilizing devices that the span will be balanced in all its positions, and still another object is a construction which will limit the upward movement of the span.

I accomplish these objects by a movable 55 beam pivotally connected to the rearwardly

extended end of the moving span and guided at its other end by a track and by a counterweight supported by the beam and the span by means of two members, the one pivotally connected to the moving span, the other pivotally connected to the beam, both of these members being pivotally connected together and further by suitably choosing the positions of the pivots and suitably shaping the track. 60

Referring to the drawings:

Fig. 1 is a side view of a bridge incorporating the preferred form of my invention.

Fig. 2 is a cross-section on line *a—a* of Fig. 1. 70

Fig. 3 is a view through pier *A²* of Fig. 1 showing an end view of the roller and tracks.

Fig. 4 is a view of an alternative construction which may be used in place of the rollers shown in Fig. 3. 75

Fig. 5 shows my invention applied to a bridge of the rolling type.

Figs. 6 and 7 show modified forms of my invention.

Similar reference numerals refer to similar parts in all the figures. Parts of the fixed structure tending to obscure the clearness of the drawings are omitted from the figures. 80

Referring to Fig. 1, *B* is the moving span of a bascule bridge, *P* the pivot or trunnion about which it revolves. *A*, *A²* and *A³* are piers, and *D* a portion of the fixed structure supporting said pivot *P*. *F¹* and *F²* are portions of the fixed approach spans. 85

W is a counterweight supported on a member or post *1* which is pivotally connected to the heel or rearwardly projecting end of the moving span *B* by the pivot *2*.

C is a beam attached to the rearwardly extended end of the span *B* by the pivot *6*. The rearward end of the said beam *C* is supported on the axle *10* of wheels or rollers *11*, said rollers *11* being free to move forward or backward on the track *T* as the bridge opens and closes. *13* are hold-down tracks to prevent lifting of the rollers off of the track *T*. The construction of these hold-down tracks is more clearly shown in the sectional view Fig. 3. For clarity of the drawing in Fig. 1 the nearer of these tracks *13* has been omitted in that figure. *8* is a post or strut member pivotally connected by pivot *7* to the member *1* supporting the counterweight *W* and to the beam *C* by pivot *9*. *c. g.* is the 90

position of the center of gravity of the span B, and G is the center of gravity of the counterweight W.

The bridge may be operated in any usual manner as by gear segment 3, secured to the moving span, and meshing with pinion 4 on a shaft 5, supported on a fixed part of the structure. Shaft 5 may be rotated by any suitable gearing and power.

10 It will be understood that the description refers to one side of the bridge only and that the parts described will in general be duplicated on the other side of the bridge.

15 The counterweight W may be constructed in a single unit as shown in Fig. 2, with connections to the trusses or girders on each side of the bridge or may be in separate units one on each side of the bridge if desired.

20 When the toe end of bridge B rises and the heel of bridge B and the beam C descend, the rollers 11 travel along tracks T, and the counterweight being controlled by members 1 and 8, also descends, and conversely when the bridge B descends, the counterweight W rises.

25 The position of the bridge and counterweight with its supporting and controlling mechanism, when the span is in its open position, is indicated by dotted lines in the figures. Slots 19 may be provided in pier A as shown in Fig. 1, and recesses 12 may be provided at both edges of the counterweight as shown in Figs. 1 and 2, to afford clearance for the girders of the span B, when the bridge is in its open position.

30 The track T, may be supported in any suitable manner as by the pier A², as shown in Fig. 1, or by structural members on said pier or by suitable connections to the girders of the approach span F¹.

35 The center of gravity G of the counterweight W, in Fig. 1, is approximately vertically over its supporting pivot 2 and it will be evident that the weight is prevented from rotation about pivot 2 and so falling over, by the member or strut 8; for should said weight tend to fall or be forced by wind pressure away from the span B, it will be held by the member 8, which will press down on beam C and tend to rotate beam C about pivot 6, causing a downward pressure on rollers 11 which is resisted by the upward reaction of track T. Should the counterweight W, tend to fall towards the span B, the rollers 11 will tend to rise and are held from so doing by the hold down rails 13, shown to larger scale in Fig. 3.

40 Having determined the position of the center of gravity c. g. of the bridge and the total weight corresponding to said center of gravity and having chosen suitable locations for the various pivots and a suitable ratio for the weight of the counterweight, 45 the path of the axle 10 and shape of track

T required to balance the bridge in all its positions may readily be determined, on the principle of virtual work, by simple graphic methods.

The shape of the track T, which depends upon the relative positions of the various pivots and the axle 10, will be curved, in order to balance the span in all its positions, unless the positions of said points and said axle are suitably chosen, but when so chosen the track T may be made straight as shown in the drawings and an accuracy of balance attained well within the limits of practice.

70 When the bridge is in its open position as shown in Fig. 1, should any force such as wind pressure be applied to the span tending to open it to a greater angle than that desired, the girders of the span B, will come into contact with the counterweight W, and the span counterweight and stabilizing mechanisms will become locked, the tendency to rotate about the pivot P, being resisted by the track T, through the beam C and link 8.

75 Referring to Fig. 3 the hold-down tracks 13 are shown as consisting of the flange angles of plate girders supported on the pier A² and braced by suitable brackets 14.

80 Fig. 4 shows an alternative construction which may be used in place of the rollers 11 and hold-down tracks 13. In the said Fig. 4, 15 is a slider mounted on the axle 10 of beam C and engaging both top and bottom surfaces of the flange of the specially shaped track T', the said track T' being firmly attached to the pier A², so as to resist any upward force on the beam C.

85 Fig. 5 shows my invention applied to a bridge of the rolling type. In this figure the center of gravity G of the counterweight W is placed to one side of the vertical through the pivot 2, thus causing this strut 8 to carry a part of the weight of the counterweight, preferably enough so that the moment of the weight W, about its pivot 2, 90 will resist any possible wind pressure tending to rotate the counterweight forward around said pivot 2 and hence no hold-down of the rollers 11 is necessary and the hold-down tracks 13 are omitted. Slots 18, are 95 provided in the pier A², in this figure to provide for clearance of the beam C, when the bridge is opened.

100 Fig. 6 shows my invention applied to a deck plate girder bridge, all the mechanism except the counterweight and its supporting members 1 and 8 being below the roadway level. It will be noted that in this figure the weight of the counterweight is carried mainly on member 8, and member 1 acts 105 mainly as a stabilizer and as in Fig. 5, the hold-down tracks 13 are not necessary and are omitted.

110 Fig. 7 shows another modification of my invention in which the positions of the pivot 130

2 of the member 1 and the pivot 6 of the beam C coincide. On account of the coincidence of these two points the pivotal point 7 cannot be fixed directly to the counterweight W, but must have a motion with respect to it. I therefore attach the strut 8 to a slider 17, by the pivot 7, said slider bearing upon the faces of the member 1 and being free to move longitudinally on said member. In order to control the motion of the slider 17 on said member 1, I introduce an additional or auxiliary member 8', pivotally connected to said slider 17, at the point 7 and to the heel 3 of the span B, at the point 9'.

Hold down tracks or their equivalent may be required with the construction shown in this figure, but for the sake of clearness they have been omitted from the drawing.

20 In Figs. 5, 6 and 7, the operating mechanism has been omitted for clearness.

In Figs. 6 and 7, track T, is shown as supported on masonry wing walls 16 on pier A². Slots 18 are preferably provided in said wall 25 to avoid interference with the motion of beam C, likewise slots 19 may be provided in piers A, to avoid interference with the motion of the span.

I prefer to place pivots 2 and 6 on the 30 line *c. g.*—P prolonged, as shown in Figs. 1 and 5, also in the form shown in Fig. 6, I prefer to place pivot 6 on said line, as thereby the graphical constructions are simplified.

Various modifications of the general arrangements and details shown may be made 35 without departing from the spirit of my invention, as for instance the roller 11, may be replaced by a sliding crosshead as shown in Fig. 4, or the end of beam C, may be carried on a long link, the roller and tracks dispensed with, and other modifications will readily suggest themselves.

Now, having described my invention, what I claim is:

45 1. In a bascule bridge the combination of a movable span having a rearwardly extended end, a counterweight above said end and pivotally supported thereon, a beam pivoted to said end and movable therewith 50 in a backward and forward direction and a strut pivotally connecting said counterweight and said beam.

2. In a bascule bridge, a movable span having a rearwardly extended end, a counterweight above said end and pivotally supported thereon, a beam pivoted to said end and movable therewith in a backward and forward direction, a roller supporting said beam on a fixed part of the bridge, and a 60 strut pivotally connecting said counterweight and said beam.

3. In a bascule bridge, a movable span having a rearwardly extended end, a counterweight above said end, and pivotally sup-

ported thereon, a beam pivoted to said end 65 and movable therewith, a roller supporting said beam, a substantially horizontal track supporting said roller and a strut pivotally connecting said counterweight and said beam.

4. In a bascule bridge, a movable span having a rearwardly extended end, a counterweight above said end and pivotally supported thereon and stabilizing means pivoted to and horizontally movable with said end to hold said counterweight above said end during motion of said span.

5. In a bascule bridge, a movable span having a rearwardly extended end, a counterweight above said end and pivotally supported thereon and means pivoted to and backwardly and forwardly movable with said end to maintain said counterweight in a vertical position during motion of said span whereby said counterweight balances said 85 span in all its positions.

6. In a bascule bridge, a rotatable span having a rearwardly extended end, a counterweight above said end, a counterweight pivot connecting said counterweight with 90 said end on the line passing through the centres of gravity and rotation of said span, a beam pivoted to said end, a pivoted strut connecting said beam to said counterweight, a roller supporting said beam and a track on 95 which said roller moves backward and forward, whereby the center of gravity of said counterweight remains vertically over said counterweight pivot during motion of said span.

7. In a bascule bridge, a movable span with girders having rearwardly extended ends, a counterweight above the roadway of said bridge, posts supporting said counterweight on said ends and pivoted thereto, 100 beams pivoted to said ends and connected to said counterweight by pivoted struts, rollers supporting the ends of said beams, and substantially horizontal tracks supporting said rollers, said tracks adapted to maintain said 110 counterweight in a vertical position over said ends during motion of said span.

8. In a bascule bridge, a movable span having a rearwardly extended end, a counterweight above said end, a counterweight pivot connecting said counterweight with said end on the line passing through the centers of gravity and rotation of said span, a beam pivoted to said end, a pivoted strut connecting said beam to said counterweight, 115 a roller supporting said beam and an horizontal track on which said roller moves backward and forward whereby the line joining said counterweight pivot and the center of gravity of said counterweight remains substantially parallel to its original 120 position during the motion of said span.

THOMAS E. BROWN, JR.
